Filed Nov. 2, 1959, Ser. No. 58,148

Term of patent 14 years

(Cl. D33—19)

Fig. 1.

Fig. 2.

Fig. 1 is a front perspective view of a triple dresser showing my new design;

Fig. 2 is a view of one of the drawers as seen in elevation from the front, but on a scale larger than Fig. 1; and

Fig. 3 is a fragmentary sectional detail view on the line 3—3 of Fig. 2.

Fig. 4 is a fragmentary sectional detail view on the line 4—4 of Fig. 1.

The back, bottom, and both sides of the triple dresser are conventional.

I claim:

The ornamental design for a triple dresser substantially as shown and described.
